UNITED STATES PATENT OFFICE

140,642

DESIGN FOR A PORTABLE PUMP APPARATUS OR SIMILAR ARTICLE

Obert G. Mandt and Arthur C. Saxe,
Columbus, Ohio

Application October 21, 1944, Serial No. 115,910

Term of patent 14 years

(Cl. D65—1)

To all whom it may concern:

Be it known that we, Obert G. Mandt and Arthur C. Saxe, both citizens of the United States, residing at Columbus, in the county of Franklin and State of Ohio, have invented a new, original, and ornamental Design for a Portable Pump Apparatus or Similar Article, of which the following is a specification, reference being had to the accompanying drawing, forming a part thereof.

Fig. 1 is a perspective view of a portable pump apparatus or similar article showing our new design; and

Fig. 2 is a similar view looking toward the opposite side of the apparatus.

We claim:

The ornamental design for a portable pump apparatus or similar article, as shown.

OBERT G. MANDT.
ARTHUR C. SAXE.
